(57) **CLAIM**

The ornamental design for a split-screen display device, as shown and described.

DESCRIPTION

FIG. 1 is a front, top and right side perspective view of a split-screen display device, showing my new design; FIG. 2 is a rear, bottom and left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of a portion of the split-screen display device shown within the area designated as 9 in FIG. 2.

The broken lines in the drawings illustrate the portions of the split-screen display device, which form no part of the claimed design.

The dash-dot-dash broken lines encircling the enlarged views are for annotative purposes only and form no part of the claim thereof.
